Charles W. Wilson Inventor
By his Attorney F. H. Gibbs

UNITED STATES PATENT OFFICE.

CHARLES W. WILSON, OF CHICAGO, ILLINOIS.

PORTABLE FORCE-DRILL.

974,454.

Specification of Letters Patent. Patented Nov. 1, 1910.

Application filed February 27, 1909. Serial No. 480,379.

To all whom it may concern:

Be it known that I, CHARLES W. WILSON, residing at Chicago, Cook county, Illinois, and being a citizen of the United States, 5 have invented certain new and useful Improvements in Portable Force-Drills, of which the following is a full, clear, and exact description, such as will enable others skilled in the art to which it appertains to 10 make and to use the same, reference being had to the accompanying drawings, which illustrate the preferred form of the invention, though it is to be understood that the invention is not limited, except as required by 15 the scope of the claims, to the exact details of construction shown and described, as it is obvious that various modifications thereof will occur to persons skilled in the art.

In said drawings: Figure 1 is an elevational view of my improved force drill; Fig. 2 is a partial longitudinal sectional view thereof on an enlarged scale; and Fig. 3 is a transverse sectional view.

The object of the invention is to produce 25 a light, compact, and easily portable force drill which comprises but few parts and which may be secured in position for operation by means of a flexible member carried thereby, which is adjustable to regulate the 30 relative position of the drill and the material to be operated upon.

Referring to the parts, 1 is a twist drill which may be of any desired form or size. 35 2 is a chuck or socket in which said drill 1 is seated.

3 is a stem carrying the chuck 2, which stem is provided with a non-circular end portion 4 adapted to be seated in the chuck end of a brace or other suitable rotating 40 implement 5 shown in fragment in Fig. 1.

The stem 3 is rotatably mounted in the sleeve 6 which is hollow as shown in the sectional view, Fig. 2, and is provided with an external screw thread 7 upon which is 45 rotatably mounted the strap clamp 8. This strap clamp is best shown in Fig. 3 and comprises the central bearing portion 8 adapted to travel on the screw thread 7 with integral lugs 9 extending laterally 50 therefrom, while forwardly of the lugs 9 are angular frame members 10 through which the strap 11 may be passed with the

perforations 12 of said strap engaging the lugs 9 before referred to.

A indicates a block or other material in 55 which a perforation is to be made by means of the drill 1 and it is to be observed that the strap 11 is passed through the openings 13 in the frame members 10 thence rearwardly toward the operating tool and the 60 perforations 12 of the strap passed inwardly upon the lugs 9 to secure the strap in position, after which rotation of the tool 5 causes corresponding rotation of the drill 1 and carries it into the material operated 65 upon.

Where slow drilling is required, the sleeve 6 is not secured upon the stem 3. If a more rapid drilling is required the set screw 14 is locked in position so as to secure said 70 sleeve 6 upon the stem 3, whereupon rotation of the stem 3 will cause corresponding rotation of the sleeve 6 and advance, by means of the screw thread in the member 8, said stem and sleeve and the drill. 75

For convenience of setting the parts to position before the commencement of drill operations, the sleeve 6 is provided with a plurality of laterally extending and rounded studs 15 which may be grasped so as to rotate 80 said sleeve by hand and advance the drill toward the material to be operated upon.

It will be observed that the lugs 9 extend outwardly beyond the opening 13 in the 85 frame 10 so that the strap is always under tension while the operation of drilling is going on, consequently there is no probability of accidental release of the parts.

What I claim is:—

1. In a portable force drill, the combination of a rotatable sleeve threaded externally, a rotatable socketed stem in said sleeve, means for locking the sleeve and stem together, and means engaging the 95 threads of the sleeve and means for connecting said last named means with the article to be operated upon for producing relative approaching adjustment of the sleeve and article. 100

2. In a portable force drill, the combination with a stem and an externally threaded sleeve surrounding the same and engaging the stem for imparting longitudinal stress

thereto, of a threaded member threaded onto said sleeve and adjustable longitudinally thereof, a frame extending from said threaded member and having strap receiving openings, a strap adapted to engage the article operated upon intermediate the length of the strap, and said strap having its ends extending through the openings of the frame, the end portions of the strap being

apertured, and lugs extending from the threaded member into the apertures of the strap.

In witness whereof I have hereunto set my hand in the presence of two witnesses.

CHARLES W. WILSON.
